UNITED STATES PATENT OFFICE.

OLGA PUMPURIN AND VALENTIN AUSRIN, OF BRONX, NEW YORK.

FLOAT.

Application filed March 14, 1927. Serial No. 175,213.

The present invention relates to a float, and has for its prime object to provide a foldable structure, which may be readily carried about when not in use, and which 5 may be readily and easily unfolded to an extended position for use in the water.

Another important object of the invention lies in the provision of a float of this nature, which has means associated therewith where- 10 by it may be propelled and steered when in the water.

A still further important object of the invention lies in the provision of a collapsible and foldable float of this nature which is 15 exceedingly simple in its construction, inexpensive to manufacture, compact and convenient, thoroughly reliable and efficient, and otherwise well adapted for the purpose for which it is designed.

20 With the above and numerous other objects in view, as will appear as the description proceeds, the invention resides in certain novel features of construction and in the combination and arrangement of parts 25 as will be hereinafter more fully described and claimed.

In the drawing, Figure 1 is a side elevation of the float showing the same extended.

Figure 2 is a top plan view of the float, 30 showing the same extended.

Figure 3 is an enlarged bottom plan view, showing particularly the steering apparatus.

Figure 4 is a perspective view of the float folded, ready to be carried about.

35 Figure 5 is a side elevation of the float folded, showing one section removed.

Figure 6 is a perspective view showing the panels only in a partially folded position.

40 Figure 7 is a rear elevation of the propeller.

Figure 8 is a rear elevation of the frame of the propeller.

Figure 9 is a side elevation of the frame 45 of the propeller.

Figure 10 is a top plan view of the propeller.

Figure 11 is a detail perspective showing a portion of the actuating lever.

50 Figure 12 is a detail section, taken through one of the pneumatic floats.

Figure 13 is a sectional view through one of the pneumatic floats, and

55 Figure 14 is a sectional view through the central panel, showing the manner in which the steering lever and seat are mounted.

Referring to the drawing in detail, it will be seen that the numeral 5 denotes a central panel preferably of square formation, having hinged to each edge a rectangular panel 6, by means of hinges 7. Two of the opposed side panels 6 have square panels 8 and 9 hinged thereto respectively, as at 10 and 11. The hinge 10 is located so that the pintles are spaced from the edge of the side 6 65 adjacent the panel 8, so that the panel 8 may be folded under the panel 9, as is indicated to advantage in Figures 5 and 6. On the ends of the other two panels 6 there are mounted inflatable pneumatic floats 14, 70 preferably of spherical formation when inflated, having straps 15 on the sides thereof, with which are engaged cables 16 or the like, which are engaged with the panels as at 17. There are preferably four of the straps 15 75

and the cable 16 for each float 14. Similar floats 14' are mounted on panels 8 and 9, by similar means 15' and 16'. When the panels are in the extended position shown in Figures 1 and 2, it will be seen that these 80 floats will support the structure in the water. It will also be apparent that the floats 14 and 14' may be deflated and that the panels may be folded as indicated in Figure 6 and then to the fully closed position as shown in 85 Figures 4 and 5.

A rudder 18 is carried by a curved bar 19, fixed to a bar 20, which is pivoted intermediate its ends as at 21 adjacent the outer edge of the panel 8. A ring 22 is 90 rotatable in the center of the panel 5 about an opening 23 and has arms 24 extending downwardly therefrom through the openings 23 and these arms support a bar 25. Cross cables 26 connect the ends of the bars 20 and 25. Legs 28 extend through the opening 23 and have a seat 29 mounted on their upper ends. The legs 28 straddle the center of the bar 25 and move in notches 29. Thus it will be seen that by turning the seats 29 through the legs 28, bar 25, cross cable 26 and bar 20, the bar 19 may be swung to move the rudder 18 for steering purposes. A pin 30 is insertable in openings 31 in the legs 28, so that they may 100 be held in a raised position, shown in Figure 1. When the structure is to be folded this pin is removed and the seat moves downwardly to rest on the panel 5.

Brackets 33 are mounted on the panel 6 110 to which the panel 9 is hinged. A propeller frame F is pivoted in the brackets 33.

This frame structure is shown to advantage in Figures 8 and 9 and includes a main bar 35 mounted on a pair of angle members 36 at one end and angle members 37 at the 5 other end. Rods 38 extend between these angle members. Straight cross members 39 are mounted on the bar 35 and V-shaped member 40 are mounted thereon. Blades 41 are hinged on the rods 38 and are limited 10 in their movement between the V-shaped members 40 and the straight members 39. The angle members 36 are pivoted, as at 42, in the brackets 33, and are connected to a link 43. This link 43 is connected to arms 15 44 as at 45. A pin 46 extends between intermediate portions of the arms 45. These arms 45 are hinged below an opening or slot 47 in the panel 6 on which the brackets 33 are mounted. This pivotal mounting is af- 20 forded by a pin 48 carried in brackets 49. An actuating lever 50 has a slotted end which straddles pins 48 and 46 and has an extension 52 hinged thereto as at 53, which may be held in an extended position by 25 means of a removable pin 54.

On the panel 5 there is mounted a socket 56 for receiving an umbrella or the like. Also on the panel 5 there is mounted a handle 57 for carrying the structure about.

30 From the above detailed description it will be seen that we have devised a float structure which is simple in its construction and when extended will support the weight of a person sitting on the seat who may propel 35 the float by the lever 50 and its extension 52. The float may be steered by turning the seat as explained. Now, when the float is not in use, the floats of a pneumatic type shown at 14 and 14' may be deflated, and then the 40 panels may be folded, as is indicated in Figure 6, and when this is accomplished the seats 29 may be let down to rest on top of the panel 5, and any suitable means may be used for holding the sections in a folded 45 position. When the float is in a folded position, it provides a very compact and convenient package to be carried around by the handle.

It is thought that the construction, utility, 50 operation and advantages of the invention will now be quite apparent without a more detailed description. It is desired, however, to point out that when the lever 50 is rocked, the blades 41 will tether, that is swing be- 55 tween the straight stop member 39 and the angular or V-shaped stop member 40 so as to propel the float forwardly, as will be quite apparent. The present embodiment of the invention has been disclosed in detail, 60 merely by way of example, since in actual

practice it attains the features of advantage enumerated as desirable in the statement of the invention and the above description.

It will be apparent that changes in the details of construction, and in the combination and arrangement of parts may be resorted to, without departing from the spirit or scope of the invention as hereinafter claimed or sacrificing any of its advantages. 65

Having thus described our invention, what 70 we claim as new is:

1. A structure of the class described comprising a central panel, a plurality of side panels hinged to the central panel, a pair of panels hinged to two of the opposed side 75 panels, floats carried by the other side panels and by the pair of panels, said floats being of the pneumatic inflatable type, a rudder hinged to one of the pair of panels, a seat structure on the central panel, means for 80 mounting the seat structure so that the same may be turned, and means associated with the last mentioned means for swinging the rudder. 85

2. A structure of the class described comprising a central panel, a plurality of side panels hinged to the central panel, a pair of panels hinged to two of the opposed side 90 panels, floats carried by the other side panels and by the pair of panels, said floats being of the pneumatic inflatable type, a rudder hinged to one of the pair of panels, a seat structure on the central panel, means for 95 mounting the seat structure so that the same may be turned, means associated with the last mentioned means for swinging the rudder, a propeller structure rockably mounted on one of the side panels and having feathered blades, and means for rocking the propeller. 100

3. A structure of the class described comprising a plurality of hingedly associated panels, for forming an extended or a folded float structure, collapsible pneumatic float elements associated with the panels, one of the panels being provided with an opening, a ring rotatable on said last mentioned panel and having arms extended through the opening and supporting a bar, a pair of legs, 105 a seat on the pair of legs, said legs straddling the bar and slideable in notches thereof, of a rudder structure, and cables extending from the rudder structure to the bar whereby the seat may be turned to steer the rudder. 110

In testimony whereof we affix our signatures.

OLGA PUMPURIN.
VALENTIN AUSRIN.
